UNITED STATES PATENT OFFICE.

SYLVESTER HEMPHILL, OF BELMONT, WISCONSIN.

HARNESS ATTACHMENT.

SPECIFICATION forming part of Letters Patent No. 286,004, dated October 2, 1883.

Application filed April 18, 1883. (No model.)

To all whom it may concern:

Be it known that I, SYLVESTER HEMPHILL, a citizen of the United States of America, residing at Belmont, in the county of Lafayette and State of Wisconsin, have invented certain new and useful Improvements in Harness Attachments; and I do hereby declare the following to be a full, clear, and exact description of the invention, such as will enable others skilled in the art to which it appertains to make and use the same.

This invention has relation to improvements in harness attachments; and the object is to construct a check-rein hook and back-strap holder in one piece not a part of the back-yoke, and which is detachable from the back-yoke.

My invention therefore consists in a holder for check-reins and back-straps in harnesses, formed with a forward turned-down check-rein hook and a back-strap loop provided with a downward-extending hook or prong, the whole adapted to set to the radical configuration of the back-yoke.

My invention further consists in the novel construction and combination of parts, as will be hereinafter more fully and specifically claimed.

In the accompanying drawings, forming a part of this specification, Figure 1 is a perspective view of my improved device attached to the back-yoke, with check-rein and back-strap fixed thereto; and Fig. 2 is a side view of the device.

The letter A represents my improved holder for check-reins and back-strap, formed with the check-rein hook B, which is turned down and bent under far enough so that the end of the hook shall rest on the back-yoke, thus forming a lock for retaining the check-rein, and securing it from accidental release. The body of the holder is formed with a step, a, and wall b, made to conform to the configuration of the back-yoke, the former serving as a rest for the holder and the latter as a guard or stay, preventing forward displacement. The after part or limb, C, is formed with a strap-hole, c, in which the back-strap is secured by any suitable means. Depending from the body is the hook D, formed to hook in the link on the back-yoke, and serves to re-

tain the holder in place, substantially as shown. The limb C of the holder is inclined, so that the end falls below the link on the yoke, the object being to obtain an upward pressure on the holder by the back-strap, which draws the step a well down on the yoke, and also presses the point of the check-rein hook down on the yoke.

It will be observed that by this construction I do not only obtain a detachable holder, but at the same time provide a self-adjusting device fully meeting all the purposes for which made.

I claim the right to vary the construction of the parts without departing from the spirit of the invention.

What I claim as my invention, and desire to secure by Letters Patent, is—

1. A holder for check-reins and back-straps, formed with a forward check-rein hook the lip of which extends back to the rest on the back-yoke, the body adapted to the configuration of the back-yoke, and the back-strap holder provided with the hook adapted to engage a staple or link on the back-yoke, substantially as described.

2. The holder for check-rein and back-straps herein described, consisting of the check-rein hook B, the body formed with the strip a and wall b, the limb C, with strap-hole c, and hook D, the whole arranged and adapted to the purposes specified.

3. In combination with a back-yoke of a harness, the check-rein and back-strap holder composed of the turned-down check-rein hook, a back-strap loop, and a downward-extending hook or prong, substantially as and for the purpose set forth.

4. In combination with a back-yoke and back-strap, the check-rein and back-strap holder composed of the turned-down check-rein hook, a back-strap loop, and a downward-extending hook or prong, substantially as and for the purpose set forth.

In testimony whereof I affix my signature in presence of two witnesses.

SYLVESTER HEMPHILL.
